Primary Examiner — Dominic Simone(74) *Attorney, Agent, or Firm* — Reinhart Boerner Van Deuren P.C.**CLAIM**

We claim the ornamental design for the tobacco can, as shown and described.

DESCRIPTION

FIG. 1 is a top perspective view of the tobacco can showing our new design, the broken line showing of embossing is for illustrative purposes only and forms no part of the claimed design;

FIG. 2 is a top view of the tobacco can of FIG. 1, the broken line showing of embossing is for illustrative purposes only and forms no part of the claimed design;

FIG. 3 is a bottom view of the tobacco can of FIG. 1; and, FIG. 4 is a left-side view of the tobacco can of FIG. 1, as the right side front, and rear are identical to the left side, these views have not been included.
